(57) **CLAIM**

The ornamental design for a towel caddy, as shown and described.

DESCRIPTION

FIG. 1 is a front right-side perspective view of a towel caddy, shown in use with a paper towel roll;

FIG. 2 is a front right-side perspective view of the towel caddy, shown in use with a paper towel roll and with the top cap removed for ease of disclosure;

FIG. 3 is a front view of the towel caddy;

FIG. 4 is a rear view thereof;

FIG. 5 is a left-side view thereof;

FIG. 6 is a right-side view of the towel caddy, shown in use with a paper towel roll;

FIG. 7 is a top view of the towel caddy;

FIG. 8 is a bottom view thereof;

FIG. 9 is an exploded perspective view of the top cap and the bottom cap components of the towel caddy, shown separately for ease of disclosure;

FIG. 10 is an exploded view of the towel caddy;

FIG. 11 is a left side view of the towel caddy, shown with the top cap and bottom cap removed for ease of disclosure;

FIG. 12 is a right side view of the bottom cap component of the towel caddy, shown separately for ease of disclosure; and,

FIG. 13 is a left side view of the top cap component of the towel caddy, shown separately for ease of disclosure.

The broken line showing of portions of the paper towel roll and pole secured to the bottom cap depict unclaimed portions of the towel caddy and form no part of the claimed design.

1 Claim, 13 Drawing Sheets
